UNITED STATES PATENT OFFICE.

FREDERICK R. MORTON, OF FRESNO, CALIFORNIA.

GRADING MACHINE.

Application filed February 8, 1921. Serial No. 443,443.

To all whom it may concern:

Be it known that I, FREDERICK R. MORTON, a citizen of the United States, residing at Fresno, in the county of Fresno and State of California, have invented certain new and useful Improvements in Grading Machines, of which the following is a specification.

My invention relates to a machine for scraping, leveling or grading land.

An important object of the invention is to provide a machine of the above mentioned character, which is well adapted for use with a small or light tractor, where certainty, precision and ease of handling the machine, by one man from the tractor seat, together with the light draft for the amount of dirt removed, are very essential.

A further object of the invention is to provide a machine of the above mentioned character, which by virtue of special features and exceeding lightness of draft, is adapted for use with horses, with slight changes.

A further object of the invention is to provide a machine of the above mentioned character having an extraordinarily light draft for the amount of earth handled or removed, which is effected by so supporting or mounting the scraper in the wheeled frame of the machine that a large amount of the pull employed in urging the scraper into the ground, is properly transferred to and carried by the wheels of the machine.

A further object of the invention is to provide means operated from the traction wheels of the machine to mechanically raise and lower the scraper blade, which means is controlled in operation by manually operated means, there being automatic means to lock the scraper against vertical movement, when the manually operated means are released.

A further object of the invention is to provide means to automatically limit the upward and downward movement of the scraper blade, when the traction wheel operated means is set into action.

A further object of the invention is to provide a clutch mechanism, included in the organization, which is simple in construction and compact.

A further object of the invention is to improve the machines of this general type,

with a view of rendering them more efficient and reliable in operation.

Other objects and advantages of the invention will be apparent during the course of the following description.

In the accompanying drawings forming a part of this specification, and in which like numerals are employed to designate like parts throughout the same.

Figure 1 is a plan view of a machine embodying my invention, 65

Figure 2 is a rear end elevation,

Figure 3 is a longitudinal section taken on line 3-3 of Fig. 1,

Figure 4 is a side elevation of the clutch mechanism, parts in section, 70

Figure 5 is a detail section taken on line 5-5 of Fig. 1.

Figure 6 is a similar view taken on line 6-6 of Fig. 1,

Figure 7 is a perspective view of bell-crank levers, included in automatic stop means, and,

Figure 8 is a perspective view of a guide bracket.

In the drawings wherein for the purpose of illustration is shown a preferred embodiment of my invention, the numeral 10 designates a main frame as a whole, preferably formed of channel or angle iron. This frame embodies longitudinal beams 11, the forward portions of which converge, at 12. The frame further comprises transverse beams 13 and 14. These several beams have connection with gusset plates 15, as shown. It is to be understood that the specific construction of the main frame may be suitably varied.

The forward end of the main frame 10 is supported by a freely swinging ground engaging wheel 16, and pivoted in a forked bracket 17, pivoted upon a vertical pin 18, suitably connected with the forward plates 15. The bracket 17 is free to turn in a horizontal plane.

The numeral 19 designates a draw bar, the rear end of which is preferably bent about the pin 18. This draw bar has connection with a chain 20, or other draft device, for connection with the tractor or harness of the draft animals.

The rear end of the main frame is supported by traction wheels 21, rigidly mounted upon a transverse axle 22, ends of which

are journalled in bearings 23, and held against longitudinal movement by collars 24, rigidly secured thereto, as more clearly shown in Fig. 2. The bearings 23 are rigidly secured to depending brackets 25, in turn rigidly secured to the beams 11.

The numeral 26 designates a scraper element as a whole, which is arranged in more or less of an upright position and is curved 10 in vertical cross-section. A blade 27 extends longitudinally of the lower edge of the scraper element 26, and is preferably detachably secured thereto. The side plates or levers 28 are secured to the ends of the 15 scraper element 26, and extend forwardly, and are apertured, to receive pivot studs 29 rigidly secured to depending brackets 30. These depending brackets are rigidly secured to the beams 11, as shown at 31. It 20 is thus seen that the scraping element is pivoted to the main frame, to swing longitudinally thereof in a vertical plane, and by virtue of the connection of the scraping element with the main frame, at a point in advance of the scraping element, the pull upon 25 the scraping element, tending to advance the same into the earth, is properly distributed to the wheels of the main frame, whereby a light draft is obtained.

30 The means to raise and lower the scraper element 26 includes a horizontal transverse control shaft 32, journalled in bearings 33, which are fixed upon bars 34, attached to short longitudinal beams 35 by any suitable 35 means in turn attached to the transverse beams 13 and 14. The control shaft 32 carries at its end a pair of forwardly projecting cranks 36, rigidly secured thereto, and links 37, Fig. 6, are pivoted to these cranks, 40 at 38. The links extend downwardly and are pivoted at 39, between pairs of ears 40, secured to the scraper element 26.

The numeral 41 designates a horizontal transverse jack shaft, journalled in bearings 45 42, supported upon the bars 34. The control shaft 32 and jack shaft 41, Fig. 3, are preferably arranged in horizontal alignment, and are spaced from the axle 22.

The numeral 43 designates a friction 50 clutch mechanism as a whole, shown more clearly in Fig. 4. This clutch mechanism embodies a central disk 44, rigidly secured to the axle or shaft 22. 45 and 46 are friction elements or drums, which are loosely 55 mounted upon the axle 22. These drums are disposed upon opposite sides of the disk 44, as shown. The friction drums are provided with tubular hubs 47 and 48, carrying sprocket wheels 49 and 50 respectively. Springs 51 are arranged between 60 the disk 44 and the hubs 47 and 48, and tend to urge the friction drums outwardly to break contact with the disk 44. The numerals 52 and 53 designate sliding blocks, 65 loosely mounted upon the axle 22, and serv-

ing to move the hubs 47 and 48 inwardly. End thrust ball bearings 53' are preferably disposed between the sliding blocks and the hubs, as shown. The sliding blocks are provided with horizontal arms 54, preferably 70 integral therewith, and extending rearwardly and having their ends flattened to slide within the grooves 55, of guide brackets 56, see Fig. 8 in particular. These guide brackets are supported by the transverse 75 bar 13. It is thus seen that the horizontal arms 54 prevent rotation of the sliding blocks 52, but permit of their free sliding movement.

The sliding blocks 52 are provided with 80 inclined or cam faces 57, contacting with inclined or cam faces 58, formed upon rotatable shifting heads 59 and 60. End thrust collars 70 are detachably mounted upon the axle 22, and adapted to be locked 85 thereto in proper adjustment by bolts 71, and end thrust ball bearings 72, are preferably interposed between the shifting heads 59 and the collar 70, as shown. The shifting heads 59 and 60 carry upstanding cranks 90 73 and 74, connected with links 75, extending rearwardly and pivotally connected with hand levers 76 and 77, as shown. The connection between each lever 76 and 77 and its corresponding link 75 is identical, as 95 shown in Figure 3. It is thus seen that when either lever 76 or 77 is swung forwardly, that the corresponding crank 73 or 74 will be swung forwardly, and the shifting head turned upon the axle 22, whereby 100 the drum 45 or 46 will be brought into frictional contact with the friction disk 44, whereby the drum is rotated. The rotation of the friction drum will be continued as long as the manually operated lever 76 or 105 77 is held in the forward position, but as soon as this lever is released, the parts are restored to the inactive position, by virtue of the spring 51 shifting the drum away from the disk.

The sprocket wheel 49 of the hub 47 is engaged by a sprocket chain 78, engaging a sprocket wheel 79, rigidly mounted upon the control shaft 32. The sprocket wheel 50 of the hub 48 is engaged by a sprocket 115 chain 80, Figures 1 and 2, engaging a sprocket wheel 81, rigidly secured upon the jack shaft 41. A gear 82 is rigidly mounted upon the jack shaft, and engages a segmental gear 83, see more particularly, Fig. 120 6, rigidly mounted upon the control shaft 32. While I prefer to employ the form of driving connection between the axle and control and jack shafts, as shown, yet the invention is in no sense restricted to the 125 same, as other form of driving means or gears may be employed.

The jack shaft 41, see more particularly Fig. 5, has a brake element or pulley 84 rigidly secured thereto, surrounded by a 130

brake band 85. One end of this brake band is secured to a beam 86, suitably connected with the beams 35, while the opposite end of the brake band carries a coupling 88, connected with a rod 89. This rod extends through and into a cylindrical casing or housing 90, rigidly secured to the beam 13. A compressible coil spring 91 is held within the housing 90, surrounds the rod 89, and engages a nut 92 upon the rod. The function of this spring is to move the rod 89 rearwardly thereby normally maintaining the brake band 85 active, holding the brake pulley 84 against turning movement.

15 The rod 89 is preferably screw threaded between its ends, at 93, for receiving an adjustable nut 94. A releasing bar 95 has an aperture 96, centrally thereof, to loosely receive the rod 89. The nut 94 is adapted to 20 contact with the releasing bar 95, and may be adjusted toward and away from this bar, by rotation of the nut 94. The bar 95 is provided at its ends with reduced extremities or trunnions 97, Figures 1, 2 and 3, 25 pivoted within openings 98, Fig. 3, formed in the levers 76 and 77. The opening 96, Figure 5 and openings 98, Figure 3, are sufficiently large to afford a loose connection between the several parts, so that when one 30 lever 76 or 77 is shifted forwardly, the bar 95 will turn upon the other lever as a pivot, when contacting with the nut 94, prior to shifting the rod 89 forwardly. Each lever 76 and 77, Fig. 5, is pivoted at its lower end, 35 at 99 to a bracket 100, secured to the beam 13.

It might be stated at this point that when the machine is drawn forwardly by a tractor, the levers 76 and 77 are preferably employed, which are directly operated by 40 hand, or cables or the like may be secured thereto, for operating the levers from the tractor.

Means are provided to limit the upward and downward movement of the scraper element, comprising a bell crank lever 101, see 45 particularly Figures 1 and 7. This bell crank lever is pivotally supported by a bracket 102, carried by the beam 14. The bell crank lever is provided at its end with an upwardly extending adjustable contact element or bolt 103, disposed in the path of travel of a stop-bracket 104, secured to the scraper element 26. The bell crank lever 101 has pivotal connection with a reach rod 50 105, extending rearwardly for pivotal connection at 106 with the lever 76. A second bell crank lever 108 is pivoted upon a bracket 109, fixed to the beam 14, and carries an adjustable contact element or bolt 110, arranged in the path of travel of a stop-bracket 111, Fig. 3, fixed to the scraping element 26. The bell crank lever 108 has 55 pivotal connection with the reach rod 112, extending rearwardly for pivotal connection 60 with the lever 77.

The operation of the machine is as follows: As the machine is drawn forwardly, the traction wheels 21 are rotated clockwise, imparting a clockwise rotation to the shaft 22. The friction drums 45 and 46 are normally held out of contact with the friction disk 44, and the spring 91 normally holds the brake band 85 into clamping engagement with the brake pulley 84, whereby the scraping element 26 is normally locked in a selected position. If it is desired to lower the scraping element, lever 76 is swung forwardly, causing rod 75 to move forwardly and swinging the crank 73 forwardly. The shifting head 59, Figure 4, is accordingly turned clockwise and the sliding block 52 shifted inwardly, whereby the friction drum 45 engages friction disk 44. At about the same time that friction drum 45 is brought into contact with friction disk 44, sufficiently for rotating friction drum 45, the lever 76 swings the corresponding end of bar 95 forwardly, causing it to contact with a nut 94, which moves the rod 93 forwardly and releases the brake pulley 84. The rotation of the axle 22, in a clockwise direction, is hence imparted to the control shaft 32, which swings cranks 36 downwardly, lowering the scraping element. This movement will continue as long as the lever 76 is manually held in the forward position, to retain friction drum 45 in contact with friction disk 44, but as soon as the lever 76 is released, the rod 89 moves rearwardly, and nut 94 shifts the lever to the rear position, the spring 51, 100 shifting the friction drum 45 outwardly. It is thus seen that the brake band 85 is automatically set as soon as the lever 76 is released. Should the operator hold the lever 76 in the forward position, the scraping element 26 would continue to descend, until stop-bracket 104 engages contact element 103, which would swing bell crank lever 101 upon its pivot, shifting rod 105 rearwardly, and automatically returning lever 76 to the 110 inactive position. Should it be desired to raise the scraping element, the lever 77 is swung forwardly, whereby a similar operation occurs, except that the shaft 32 is turned counter-clockwise, shifting the cranks 36 upwardly, and raising the scraping element. The upward movement of the scraping element is limited by the stop bracket 111 engaging the contact element 110 which would swing bell crank lever 108 upon its pivot 120 and restore the lever 77 to the inactive position. It is thus seen that means are provided to automatically limit the downward and upward swinging movement of the scraping element, and as soon as this movement is stopped, the brake mechanism is set to lock the element in its position.

It is to be understood that the form of my invention herewith shown and described is to be taken as a preferred example of the 130

same, and that various changes in the shape, size and arrangement of parts may be resorted to without departing from the spirit of my invention or the scope of the subjoined claims.

Having thus described my invention, I claim:

1. In a machine of the character described, a main frame, wheels for supporting the same, a vertically movable scraper element connected with the frame, a rotatable driving shaft connected with the main frame, means to raise and lower the scraper element, separate driving connecting means between the rotatable shaft and the first named means, a clutch device for rendering each driving connecting means active, a brake device for holding the scraper element in a selected position, means for actuating each clutch device, and means operated upon the operation of either of the clutch actuating means to release the brake device.
2. In a machine of the character described, a main frame, wheels for supporting the same, a vertically movable scraper element connected with the frame, a rotatable driving shaft connected with the main frame, means to raise and lower the scraper element, separate driving connection means between the rotatable shaft and the first named means, a clutch device for rendering each driving connecting means active, a brake device for holding the scraper element in a selected position, pivoted elements for actuating the clutch devices, a member connected with said pivoted elements and adapted to be moved by the movement of either element, and means operated by the member and adapted to release the brake device.
3. In a machine of the character described, a main frame, wheels for supporting the same, a vertically movable scraper element connected with the frame, a rotatable driving shaft connected with the main frame, means to raise and lower the scraper element, separate driving connection means between the first named means and the rotatable shaft, clutch devices for rendering the driving connecting means active, a brake device for holding the scraper element in a selected position, levers connected with the clutch devices to operate them, a bar pivotally connected near its ends with said levers, and a rod engaging the bar between its ends and connected with the brake device.
4. In a machine of the character described, a main frame, wheels for supporting the same, a vertically movable scraper element connected with the main frame, a rotatable driving shaft connected with the main frame, a control shaft connected with the frame and having connection with the scraper element, a jack shaft connected with the main frame, an inner clutch element connected with the rotatable shaft for rotation therewith, outer clutch elements to engage and disengage the inner clutch element, driving connecting means between one outer clutch element and the control shaft, driving connecting means between the other outer clutch element and the jack shaft, reverse driving connecting means between the jack shaft and the control shaft, levers having means to shift the outer clutch elements, a brake device carried by the jack shaft, a bar connected with the levers, and means to operate the brake device and adapted to be operated by said bar.
5. In a machine of the character described, a main frame, wheels for supporting the same, a vertically movable scraper element connected with the frame, a rotatable driving shaft connected with the main frame, means to raise and lower the scraper element, separate driving connecting devices between the rotatable shaft and the first named means, clutch devices for rendering said driving connecting devices active, a brake device for holding the scraper elements in a selected position, pivoted elements for actuating the clutch devices, a member connected with the pivoted elements and adapted to be moved by the movement of either element, means operated by the member and adapted to actuate the brake device, means operated upon the upward movement of the scraper element beyond a predetermined distance to shift one pivoted element, and means operated by the downward movement of the scraper element beyond a predetermined distance to shift the other pivoted element.
6. In a machine of the character described, a main frame, a vertically movable scraper element connected therewith, normally inactive means to raise the scraper element, normally inactive means to lower the scraper element, levers connected with the separate means to render them active, a common element connecting said levers and adapted to be moved by the movement of either lever, a brake device normally holding the scraper element against vertical movement, a rod connected with the brake device and engaging the common element, and a spring moving the rod in one direction.

In testimony whereof I have affixed my signature in presence of two witnesses.

FREDERICK R. MORTON.
